UNITED STATES PATENT OFFICE.

PHILIP JOSEPH PARMITER, OF ANSTY, ENGLAND.

BICYCLE-BRAKE.

SPECIFICATION forming part of Letters Patent No. 643,231, dated February 13, 1900.

Application filed May 29, 1899. Serial No. 718,763. (No model.)

To all whom it may concern:

Be it known that I, PHILIP JOSEPH PARMITER, a subject of the Queen of Great Britain, residing at Ansty, near Salisbury, England, have invented certain new and useful Improvements in Brakes for Cycles, of which the following is a specification.

My invention relates to brakes for cycles, and it consists in the novel features herein-
10 after described, reference being had to the accompanying drawings, which illustrate one form in which I have contemplated embodying my invention, and said invention is fully disclosed in the following description and
15 claims.

Referring to the said drawings, Figure 1 is a view of a portion of a bicycle, showing the preferred form of my invention applied thereto. Fig. 2 is a front elevation of the same,
20 partly in section.

According to my invention I employ a brake frame or spoon in the form of a segment of a cylinder carrying a flexible endless friction-band of greater length than the spoon, said
25 spoon and band being adapted to be pressed into engagement with the tire of the wheel, whereby the endless band will be caused to revolve and the friction between the inner surface of the band and the outer face of the
30 spoon will cause the wheel to be retarded without wear upon the tire.

In the drawings, *a* represents the frame of the bicycle, and *A* the rear wheel thereof.

b represents the brake frame or spoon, and
35 *c* represents the endless friction-band. The brake frame or spoon *b* is secured to the lower end of a vertical brake-lever *f*, having a foot-rest at its upper end. The endless band is prevented from accidentally disengaging the
40 frame or spoon *b* by a guiding or retaining flange *b'* on one side and the brake-lever *f* on the other side, the portion *b'* of which adjacent to the spoon forms a similar retaining or guiding flange. The lever *f* is pivoted by
45 a stud *h'* to a clip *h*, which is constructed to detachably engage one of the bars of the cycle-frame, said clip *h* extending around the bar and being provided with a set-screw *i*.

j represents a stop-plate adapted to be inserted between the frame-bar and the screw *i* and provided with a lateral projection or stop to limit the movement of the said lever *f* in a

direction to move the spoon *b* away from the wheel *A*. The plate *j* can be adjusted to the desired position and clamped by the screw *i*, 55 which also secures the clip *h* to the bar.

The position of the brake-lever *f* is such that a downward pressure thereon will not apply the brake, but will allow the rider to rest his feet upon it or to use it as a step to 60 dismount, if desired. To apply the brake, the rider will place his foot on the upper end of the lever *f* and press it forward, thereby moving the spoon *b* and the endless band rearwardly into engagement with the wheel. 65 It will be observed that the band *e* runs free from contact with the spoon for nearly half of its length, so that the band cannot bind or stick in revolving, as it would be apt to do if it were placed around a cylindrical support. 70 In this construction the band must always move freely and easily under the spoon. It will also be seen that as the lever *f* is only connected to the spoon at one side the band *e* can be removed and replaced or renewed 75 without disturbing any other part of the brake.

What I claim, and desire to secure by Letters Patent, is—

1. A wheel-brake comprising among its 80 members a curved spoon, having a short convex band-engaging surface, an endless band of greater length than said band-engaging surface of the spoon, and having only a portion of its inner surface engaging said spoon, 85 the remaining portion being entirely out of contact with said spoon, lateral guides on said spoon to prevent the accidental displacement of said band, a vertically-disposed lever having one end rigidly secured to said 90 spoon at one side of the same and its other end provided with a foot-engaging portion, and a stop for engaging said lever when the latter is moved in a direction to move the spoon and band away from the wheel; where- 95 by said lever may be used as a step and foot-rest and whereby the band can be removed from the spoon and replaced without moving said lever, substantially as described.

2. A wheel-brake comprising among its 100 members an endless friction-band, a curved spoon of less extent than the said band, engaging a portion of the inner surface of said band, and provided with lateral guides for

said band, the portion of said band not in contact with said spoon being entirely free, a vertically-disposed lever secured at its lower end to said spoon, a clip pivotally connected to said lever and an adjustable plate adapted to be inserted in said clip, provided with a stop for limiting the movement of said lever

5

in a direction to move said spoon away from the wheel, substantially as described.

PHILIP JOSEPH PARMITER.
